CLAIM

We claim the ornamental design for a mixer, as shown and described.

DESCRIPTION

FIG. 1 is a front isometric view of an embodiment of a mixer showing our new design;

FIG. 2 is a front elevation view thereof;

FIG. 3 is a back elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines shown are included for purposes of illustrating portions of the mixer that form no part of the claim.
